(57) **CLAIM**

The ornamental design for a tire, as shown and described.

DESCRIPTION

FIG. 1 is a perspective view of a tire of the present application taken generally from the front and a first side thereof;

FIG. 2 is a front view thereof;

FIG. 3 is a right side view thereof;

FIG. 4 is a left side view thereof;

FIG. 5 is an enlarged partial, perspective view, again taken generally from the front and a first side thereof;

FIG. 6 is an enlarged partial, front view thereof;

FIG. 7 is an enlarged partial, right side view thereof; and,

FIG. 8 is an enlarged partial, left side view thereof.

The broken lines depicted as dot-dash lines in the figures are intended to indicate the demarcation of where corresponding enlarged fragmentary view(s) originate.
